CLAIM

The ornamental design for a display screen with animated graphical user interface, as shown and described.

DESCRIPTION

FIG. 1 is a front view of a first image in a sequence of a display screen with animated graphical user interface showing our new design;

FIG. 2 is a front view of a second image thereof;

FIG. 3 is a front view of a third image thereof;

FIG. 4 is a front view of a fourth image thereof;

FIG. 5 is a front view of a fifth image thereof;

FIG. 6 is a left side view thereof, with the right side view being a mirror image thereof; and,

FIG. 7 is a top plan view thereof, with the bottom plan view being identical thereto.

The appearance of the display screen with animated graphical user interface sequentially transitions between the images shown within FIGS. 1-5. The process or period in which an image sequence transitions from one image to another image forms no part of the claimed design. The broken lines of uneven length shown in the drawings form a boundary of the claimed design. The broken lines of even length shown in the drawings illustrate portions of the article which form no part of the claimed design.
